VEHICULAR TANK FOR FUEL OR THE LIKE

James M. Yates, 908 Deer Ridge, Waco, Tex. 76710

Filed Nov. 16, 1970, Ser. No. 26,002

Term of patent 14 years

Int. Cl. D12—16

U.S. Cl. D14—3

FIG. 1

FIG. 2

FIG. 3

FIG. 4

FIG. 5

FIG. 6

FIG. 7

FIG. 1 is a front perspective view of a vehicular tank for fuel or the like in accordance with the design of my new design;

FIG. 2 is a top plan view thereof;

FIG. 3 is a front elevation view thereof;

FIG. 4 is a right side elevation view thereof;

FIG. 5 is a bottom plan view thereof;

FIG. 6 is a rear elevation view thereof; and

FIG. 7 is a left side elevation view thereof.

I claim:

The ornamental design for a vehicular tank for fuel or the like, substantially as shown.
